HAULING SCRAPER

Wayne H. McGlade, Indianapolis, Ind., assignor
to J. D. Adams Manufacturing Company,
Indianapolis, Ind., a corporation of Indiana

Application August 3, 1940, Serial No. 350,989

1 Claim. (Cl. 37—126)

My invention relates to hauling scrapers, and more particularly to that type of hauling scraper in which there is provided for the open front end of the bowl a movable closure which will prevent the escape of earth from the bowl before emptying of the bowl is desired.

One of the main objects of my invention is to operate the movable closure and the bowl by a common operating means while insuring that the bowl will not be dumped until the closure is completely out of the way. Another object of my invention is to provide an improved means for raising and lowering the bowl to control its elevation both during filling and hauling. A further object of my invention is to provide means facilitating return of the bowl to normal position after it has been dumped.

In carrying out my invention, I employ a frame comprising front and rear sections pivotally interconnected on a horizontal transverse axis between front and rear supporting wheels. The scraper bowl is pivotally mounted on the rear section in advance of the rear wheels, and is swingable between its loading and dumping positions about its axis of pivotal mounting. To control the height of the bowl the relative disposition of the two frame-sections about their axis of pivotal interconnection is varied; and for this purpose, I employ a thrust member which is pivotally connected to the rear frame-section above such axis and which extends forwardly over the front frame-section, where a mechanism including sheaves and a cable is arranged to move the thrust member rearwardly and thus raise the bowl. The bowl-closure is movably mounted on the rear frame section, and is raised from bowl-closing position by means which reacts upon the bowl and tends to tilt it from loading to dumping position. A latch, normally operating to hold the bowl in loading position, is arranged to be automatically released when the closure is fully raised. Associated with the bowl is a yielding means arranged to be stressed by movement of the bowl into dumping position and therefore to exert on the bowl an effort tending to return it to loading position.

The accompanying drawings illustrate my invention: Fig. 1 is a fragmental plan view of the scraper; Fig. 2 is a side elevation of the scraper showing the bowl elevated into the hauling position; Fig. 3 is also a side elevation, but showing the bowl in loading position; Fig. 4 is a fragmental side elevation showing the bowl-closure raised and the bowl in dumping position; Fig. 5 is a fragmental plan view of the sheave-and-

cable mechanism employed to control elevation of the bowl; Fig. 6 is a vertical section on the line 6—6 of Fig. 5; Fig. 7 is a horizontal section through the axle-post on the front frame-section; Fig. 8 is a fragmental side elevation, in partial section, of the latch which operates normally to hold the bowl in loading position; and Fig. 9 is a rear elevation of such latch mechanism.

As will be clear from Figs. 1 and 2, the frame 10 of the scraper comprises a front section 10 and a rear section 11 pivotally interconnected by pivot pins 12 disposed in alignment with each other at opposite sides of the frame. The rear frame-section 10 is provided at its rear end with coaxial supporting wheels 13. The front frame section is desirably arched to provide clearance for the front wheels and has at its front end a downwardly projecting axle post 14, desirably of box-section as illustrated in Fig. 7. An axle shank 15 (see Fig. 2) is rotatably mounted on a vertical axis in the post 14; and the front axle 16 of the scraper is pivoted to the shank 15 on a horizontal axis as by means of a pivot bolt 17. A draft-tongue 18, pivoted to the front axle for swinging movement in a vertical plane, extends forwardly for connection to a tractor by means of which the scraper is drawn. Front wheels 19 are mounted on suitable spindles at opposite ends of the axle 16.

30 A scraper-bowl 25 is pivoted near its open front end to the rear frame-section 11 by means of trunnions 26 and is swingable about such trunnions between the carrying and loading position shown in Figs. 2 and 3 and the dumping position shown in Fig. 4. Because the trunnions 26 are located near the front of the bowl, the weight of the bowl tends to cause its rear end to drop; and to limit such movement of the bowl, it may be provided at its rear end with one or more ears 27 (Fig. 1) which engage the upper surface of a cross-member 28 on the rear frame-section 10.

40 The preferred form of closure for the front end of the bowl comprises an apron 30 which projects forwardly and upwardly from the cutting edge of the bowl and with which there are associated two wings 31 which extend upwardly from the apron and are provided with rearward extensions overlapping the side walls of the bowl 25. The closure is mounted on the forward ends of arms 33 whose rear ends are pivoted to the rear frame-section on trunnions 34 above the bowl.

50 The elevation of the bowl, both during loading and during hauling, is controlled through the medium of a thrust member 36 which is pivoted to the front end of the rear frame-section on an

axis spaced well above the pivot pins 12. The thrust member 36 desirably comprises a tubular cross member 37, which has rigid with it at its ends arms 38 pivoted to the rear frame-section 11 by trunnions 39, and a pair of opposed channel members 40 secured to the cross member 37 and extending forwardly therefrom above the front frame section 10, the front ends of such channels being interconnected by a cross-piece 41. To provide additional rigidity, oblique braces 42 may extend between the front ends of the channels 40 and the opposite ends of the cross-member 37.

Mounted on the front frame section 11 between the channels 40, I dispose a set of coaxial sheaves 45. A cooperating set of sheaves 46 is mounted between the channels 40 at the front ends thereof. A cable 47, conveniently having its dead end secured, as at 48, to the front end of the thrust member 36, is reeved between the two sets of sheaves 45 and 46, the free end of the cable passing downwardly from the last sheave 45, around a direction-changing pulley 49 swiveled on a vertical axis at one side of the axle-post 14, and thence forwardly to suitable hoist mechanism (not shown) on the tractor which draws the scraper.

Conveniently, the sheaves 45 are mounted on a common fixed shaft 51 which is supported in a bracket 52 on the front frame section 10 and the ends of which project beyond such bracket to support rotatably a pair of guide rollers 53 received respectively in the channels 40, as will be clear from Figs. 5 and 6.

For the purpose of operating the bowl 25 and bowl-closure 30-31, I employ a second cable 55. This cable may have its free end anchored, as at 56 (Fig. 1), to the thrust member 36 and is reeved between a set of sheaves 57 at the rear end of the bowl and a second set of sheaves 58 rotatably supported above the cross member 37. Leaving the last sheave 58, the cable 55 extends downwardly, around a sheave 59 on the apron 30, upwardly over pulleys 60 and 61 on the front frame-section, again downwardly and around a second direction-changing pulley 62 swiveled on a vertical axis at the side of the axle-post 14, and thence forwardly to the hoist mechanism on the scraper-pulling tractor.

It will be noted that, with the parts arranged as just described, the application of tension to the cable 55 will tend both to raise the closure 30-31 and to tilt the bowl 25 toward its dumping position. As it is desired that the closure be out of the way before the bowl is dumped, I provide means for insuring that tension in the cable 55 will not cause dumping movement of the bowl until after the elevation of the closure has been completed.

To accomplish the result just noted, I mount on the rear frame-section 11 in rear of the bowl a transverse rock shaft 65 (Figs. 8 and 9) rigid with which is a forwardly and downwardly extending latch member 66 whose free end engages an abutment 67 on the rear wall of the bowl 25 and prevents the bowl from tilting toward dumping position. For the purpose of rocking the shaft 65 to release the latch 66, there is rigidly secured to the shaft near its outer end an arm 68 connected by a pin 69 to a block 70 clamped between two nuts 71 on the screw-threaded lower end of a rod 72. The rod 72 extends generally upwardly from the block 70, its upper end being slidably received in a guide 73 (Figs. 2 and 4) located on the rear frame section in rear of one of the trunnions 34. The adjacent closure-sup-

porting arm 33 is provided with a rigid finger 74 positioned to engage the upper end of and depress the rod 72 to rock the shaft 65 and release the latch 66 as the closure reaches elevated position. A spring 75, acting between the rod 72 and the rear frame section tends yieldingly to raise the rod and hold the latch in engaged position. Movement of the latch under the influence of the spring 75 may be limited by arranging the arm 68 so that it will engage the cross-member 28, as indicated in Figs. 8 and 9.

In the operation of the scraper, the weight of the parts between the front and rear wheels tends to cause the two-section frame to drop in the middle and the trunnions 39 and thrust member 36 to move forwardly relative to the front frame-section 10, such tendency being opposed by tension in the cable 47. Accordingly, the elevation of the bowl can be controlled by winding the cable 47 on or unwinding it from the hoist mechanism on the scraper-drawing tractor. When the bowl is being loaded, it is held in its normal position on the rear frame section by the latch 66, and the cable 47 is adjusted so that the cutting edge of the bowl will be below the level of the earth with which the bowl is to be filled, as is illustrated in Fig. 3. During the filling of the bowl, the cable 55 is adjusted to hold the closure 30-31 in the position shown in Fig. 3 with the rear edge of the apron 30 slightly above ground level. As the scraper is drawn over the ground, the earth dislodged by the cutting edge of the bowl fills the bowl, some of such earth falling forwardly where it lodges on the apron 30.

When the bowl has been filled to the desired extent, the cable 47 is pulled forwardly, thus shortening the distance between the two sets of sheaves 45 and 46 and moving the thrust member 36 rearwardly. This operation changes the angular relationship of the two frame-sections 10 and 11 about their axis of interconnection and raises the bowl to the hauling position shown in Fig. 2. Simultaneously, the closure 30-31 is lowered relative to the bowl to close the front end thereof. The scraper, with its load of earth, may now be hauled to the place where it is to be dumped.

It is to be noted that the guide rollers 53, which are co-axial with the sheaves 45 and 58 which have a diameter only slightly smaller than the internal width of the channels 40, maintain those channels in coplanar relationship with the sheaves. As a result, tension in the cable stretches between the sheaves 45 and 46 imposes no bending effort on the channels. Bowl-raising adjustment of the frame may be limited, as by the provision of co-operating stops 80 and 81 on the bracket 52 and arm 36. (See Fig. 6.)

When the scraper reaches the place where it is to be dumped, the cable 55 is adjusted to raise the closure 30-31. At the same time the cable 55 applies a raising effort to the closure it also applies to the bowl, through the sheaves 57, an effort tending to tilt the bowl forwardly about the trunnions 28. Because of engagement of the latch 66 with the abutment 67 on the bowl, however, the bowl is positively prevented from tilting until after the closure has been raised high enough for the finger 74 to engage and depress the rod 72 to release the latch 66. As the closure reaches latch-releasing position its further upward movement is limited, as by arranging the wings 31 to engage the cross member 37. Thereafter, continued

shortening of the cable 55 will swing the bowl forwardly to dumping position, as shown in Fig. 4. The nuts 71 on the rod 72 permit control of the latch-releasing position of the closure 30-31.

As will be apparent from Fig. 4, when the bowl is in dumped position it is so nearly vertical that its weight is relatively ineffective to cause its return to normal position. I therefore prefer to equip the scraper with means tending to return the bowl to its normal position. In the device shown, this means takes the form of a tension spring 85 secured at one end to the rear portion of the frame-section 11 and extending forwardly and upwardly therefrom, its front end being attached to a chain 86 which extends and is secured to an elevated point at the front of the rear frame-section. At an intermediate point on the chain 86, there is secured a sleeve 87 having a flange adapted to be engaged by a bifurcated bracket 88 on the side wall of the bowl as the bowl approaches dumping position. In dumping position of the bowl, the spring 85 is strained materially, as is clear from Fig. 4, and accordingly the sleeve 87 exerts on the bracket 88 a force tending to

swing the bowl rearwardly toward normal position. As soon, therefore, as tension in the cable 55 is released, the bowl, aided by the spring 85, and the closure 30-31 return to their normal positions under the influence of gravity. There may be a bowl-returning mechanism 85-86-87-88 on each side of the machine if desired.

I claim as my invention:

- 10 In a hauling scraper, a wheel-supported frame, a bowl mounted on said frame and tiltable between loading and dumping positions, and yielding means mounted on said frame in position to be engaged by said bowl as it approaches dumping position and to exert on the bowl a force tending to restore it to loading position, said yielding means comprises a tension spring secured at one end to said frame and a flexible element connected to the opposite end of said 15 spring and extending to a remote point on said frame, said bowl and flexible element being provided with co-operating abutments engageable with each other to stress the spring as the bowl 20 approaches dumping position.
